ABSTRACT OF THE DISCLOSURE

This telescoping auxiliary gun stock attachment has a mounting plate or rearward bracket which is secured to the end of the remaining portion of the shortened regular gun stock of the rifle or other firearm. Extending forward from the mounting plate with its axis offset to the left from the axis of the rifle barrel to avoid conflict with the magazine cartridge clip holder is an elongated tube to the forward end of which is secured an upwardly-inclined and also similarly-offset rod or forward bracket, the upper end of which is secured to the forward sling swivel of the firearm. Telescopingly mounted within the tube is the stem of an auxiliary gun stock having a perpendicularly-bent approximately D-shaped auxiliary butt loop. The stem is an elongated rod carrying a cross pin which projects through and slides in an elongated slot in the tube and is notched at two locations to receive the detent lug on the end of a spring detent arm to hold the auxiliary stock in its extended and retracted positions respectively. This invention enables the firearm to be packed into a smaller space for transportation or storage than a conventional firearm.

In the drawings:

FIG. 1 is a side elevation of a firearm, particularly a bolt action repeating rifle, equipped with a telescoping auxiliary stock attachment, according to one form of the invention, with the auxiliary stock in its extended position;

FIG. 2 is a side elevation similar to FIG. 1, but with the auxiliary stock in its retracted position;

FIG. 3 is an enlarged side elevation, partly in vertical section, of the auxiliary gun stock shown in FIGS. 1 and 2, with a portion of the elongated rod or stem of the stock broken away to conserve drawing space;

FIG. 4 is a rear elevation looking in the direction of the arrows 4-4 in FIG. 3;

FIG. 5 is a vertical section taken along the line 5-5 in FIG. 3;

FIG. 6 is a fragmentary plan view looking downward at an angle indicated by the arrows 6-6 in FIG. 3; 50 and

FIG. 7 is a cross-section taken along the line 7-7 in FIG. 3.

Referring to the drawings in detail, FIG. 1 shows a firearm, generally designated 10, for example a conventional bolt-action repeating rifle equipped with a telescoping auxiliary gun stock attachment 12 according to one form of the present invention. To attach the auxiliary gun stock attachment 12, the rearward portion of the rifle gun stock 14 behind the pistol grip portion 15 has been removed along a substantially vertical facing or surface 16. The rifle 10 is equipped with a conventional bolt-action mechanism 18 receiving cartridges from an arcuately curved hollow clip magazine 20 disposed immediately below the cartridge chamber (not shown) in the rearward end of the rifle barrel 22. The forestock 24 and the fore-grip 26, usually of wood, surround the rearward portion of the rifle barrel 22 and are held in assembly at their forward ends by a sling swivel 28 having the usual clamping bolt 30 at its lower end. The bolt-action mechanism 18, as usual, is actuated by the conventional trigger 32 within the trigger guard 34.

2

The telescoping auxiliary gun stock attachment 12 includes a mounting plate or rearward bracket 36 secured as by screws or other fasteners 38 to the surface or facing 16 of the remainder of the rifle gun stock 14. Secured as by welding to the forward face of the mounting plate 36 is a swivel boss 40, the upper and lower ends of which are provided with sockets or blind holes 42 in which are seated and pivotally mounted the opposite end portions 44 of an approximately D-shaped rearward sling swivel 46. The mounting plate 36 is vertically elongated with a leftward offset lower end portion 48 containing a hole 50 which is welded or otherwise secured the rearward end of an elongated supporting tube 52. Mounted in the forward end of the supporting tube 52 is the rearward end or shank 54 of a leftward- and vertically-offset forward bracket 56 consisting of a bent rod having an intermediate portion 58 inclined at a compound or skew angle both to the horizontal and to the vertical and having a tapered upper portion 60 with a flattened end portion 62 containing a horizontal hole 64. The flattened end portion 62 fits between the two opposing lower ends of the forward sling swivel 28 and is clamped in position by the clamping bolt 30 passing through the hole 64. Instead of the separate forward bracket 56, the invention contemplates that the forward end portion of the tube 52 will be similarly bent upward and leftward and similarly secured to the forward sling swivel.

The supporting tube 52 is provided with a pair of aligned elongated longitudinal slots 68 (FIGS. 1, 2 and 30 7) in which ride the opposite ends of a stop pin 70, the intermediate portion of which passes through and is secured in the stem or auxiliary stock rod 72 of the auxiliary stock, generally designated 74. The rearward end of the stock rod or stem 72 terminates in an upstanding 35 approximately D-shaped auxiliary butt 76 in the form of a rectangular loop (FIG. 4) including a lower horizontal arm 78, a vertical arm 80, an upper horizontal arm 82 and a vertical end portion 84 separated by a gap 86 from the rod or stem 72. The plane of the auxiliary 40 butt loop 76 is substantially perpendicular to the axis of the rod or stem 72. The latter is provided with longitudinally-spaced forward and rearward notches 88 and 90 respectively (FIG. 1) which are selectively engaged by the upturned detent lug 92 on an angle arm 94 which 45 in turn is riveted or otherwise secured to the leaf spring 96 of a spring detent, generally designated 98, the forward end of which is riveted or otherwise secured as at 100 to the lower side of the supporting tube 52.

In the operation of the invention, let it be assumed that the parts of the auxiliary gun stock attachment 12 are in the telescoped or retracted position shown in FIG. 2, such as for transportation or storage, and that the user wishes to prepare it for firing. To do so, he grasps the butt loop 76 and pulls on it while he pushes downward on the detent spring 96 to withdraw the detent lug 92 from the rearward notch 90. With the auxiliary stock thus freed for extension movement, he continues to pull rearwardly on the butt loop 76 until the forward notch 88 arrives in alignment with the detent lug 92, whereupon the force of the leaf spring 96 pushes the lug 92 into the forward notch 88 and locks the auxiliary stock 74 in its extended position FIG. (1). The firearm 10 is then used in the ordinary manner.

To retract the auxiliary stock 74, the user reverses the foregoing procedure by pressing downward upon the leaf spring 96 to withdraw the detent lug 92 from the forward notch 88 while he presses forward against the butt loop 76, causing the rod or stem 72 to slide into the supporting tube 52 until the detent lug 92 is again urged into the rearward notch 90 by the leaf spring 96. The parts are now in the positions shown in FIG. 2. Meanwhile, the

action of the stop pin 70 not only serves to limit the sliding motion of the rod or stem 72 but also prevents relative twisting or rotation between it and the supporting tube 52.

I claim:

1. A telescoping auxiliary gun stock attachment adapted to be secured to the shortened stock of a conventional firearm having a forward sling swivel, said attachment comprising

forward and rearward brackets adapted to be secured in depending spaced relationship to the forward and rearward end portions respectively of the shortened firearm stock,

an elongated approximately horizontal tubular support secured to the lower portions of said forward and rearward brackets,

and an auxiliary gun stock having a rod portion slidably rearward brackets, and

an auxiliary gun stock having a rod portion slidably engaging said tubular member in telescoping relationship therewith and having an upstanding auxiliary butt portion secured to the rearward end of said rod portion.

2. A telescoping auxiliary gun stock attachment, according to claim 1, wherein said rod portion has a plurality of spaced detent portions thereon and wherein a detent member is mounted on said tubular support in selective engageability with said detent portions.

3. A telescoping auxiliary gun stock attachment, according to claim 1, wherein means is provided between said support and said rod portion for preventing relative angular motion while permitting relative sliding motion therebetween.

4. A telescoping auxiliary gun stock attachment, according to claim 1, wherein the lower portions of said forward and rearward brackets are offset leftward relatively to said firearm stock.

5. A telescoping auxiliary gun stock attachment, accord-

ing to claim 1, wherein the forward end of said forward bracket is constructed and arranged to be secured to the forward sling swivel of the firearm.

6. A telescoping auxiliary gun stock attachment, according to claim 1, wherein a rearward sling swivel is secured to said rearward bracket.

7. A telescoping auxiliary gun stock attachment, according to claim 3, wherein said means comprises an elongated slot in said tubular support and a transverse element secured to said rod portion within said tubular support and projecting into said slot.

8. A telescoping auxiliary gun stock attachment, according to claim 1, wherein said auxiliary butt portion comprises an open-centered loop disposed substantially perpendicularly to said rod portion.

9. A telescoping auxiliary gun stock attachment, according to claim 8, wherein said loop comprises a bent portion of said rod portion integral therewith.

10. A telescoping auxiliary gun stock attachment, according to claim 1, wherein said forward bracket comprises a rod element having a rearward portion secured in the forward end portion of said tubular support and having a forward end portion disposed above and offset leftward of said forward end portion of said tubular support.
